UNITED STATES PATENT OFFICE

ARNOLD L. STERN, OF CLEVELAND HEIGHTS, OHIO

DESIGN FOR A DISPLAY DEVICE

Application filed January 3, 1931. Serial No. 38,192. Term of patent 3½ years.

To all whom it may concern:

Be it known that I, ARNOLD L. STERN, a citizen of the United States, residing at 2955 Edgehill Road, Cleveland Heights, in the county of Cuyahoga and State of Ohio, have invented a new, original, and ornamental Design for Display Device, of which the following is a specification, reference being had to the accompanying drawing, forming part hereof, wherein the figure is a perspective

view of a display device showing my new design. The device is a unitary article of manufacture (consisting, however, of separable elements) and the opposite sides of the device are identical with each other in appearance.

I claim:

The ornamental design for a display device as shown and described.

ARNOLD L. STERN,
